UNITED STATES PATENT OFFICE

WILHELM DAVID, OF HAMBURG, GERMANY, ASSIGNOR TO E. P. LEHMANN, OF BRANDENBURG-ON-THE-HAVAL, GERMANY

SEESAW TOY

Application filed February 3, 1931, Serial No. 513,162, and in Germany February 5, 1930.

The invention relates to a toy forming a seesaw. In toys of this class it is known to produce the seesaw motions by means of dropping sand or balls. Now according to the present invention the motion of the seesaw beam is obtained by the fact that each of the two arms of the beam is hingedly connected to a member having several superposed steps, which two members cooperate in such a manner that a ball dropping thereonto alternatively drops from the step of the one member onto the following step of the other member.

From the last step the balls drop onto a lever which by means of a thrust rod feeds new balls to the stepped path.

In order that the invention may be more readily understood, an embodiment of the same is illustrated by way of example which forms a seesaw fitted with the actuating device according to the invention; the invention may however serve to produce any other seesawing motion with toys of any kind.

The beam *a* of the seesaw on the ends of which are fixed dolls or the like, is fulcrumed at *c* on the frame *d* of the toy. On each side of the fulcrum *c* is pivoted on the beam *a* ladder-like members *e*₁ and *e*₂, respectively, which members are interconnected by an upper link *f* fulcrumed at *f*₁ on the frame *d*.

As will be seen the steps *g* of the ladders *e*₁, *e*₂ are staggered relatively to one another. Above the ladders is provided a feeding trough *h* for the balls *i*. Two balls are fed at the beginning of the actuation, the first ball abutting on a stop *k*. This first ball rests on a hole through which may project a thrust rod *l* pivoted at *l*₁ on a lever *m*.

The described toy operates as follows:

As soon as the first ball *i* has been pushed over the stop *k*, it drops alternatively from a step *g* of the one ladder *e*₁ onto the next step of ladder *e*₂, whereby the left-hand and right-hand arm of the beam *a* is lowered alternatively so that a continuous seesaw motion of the beam *a* is obtained.

As soon as the ball drops from the last step onto the lever *m*, the latter is depressed and rod *l* pushes the next ball over the stop *k*, so that the seesaw is now held in motion by this

other ball. If always two balls are present behind the stop *k*, the beam executes an uninterrupted seesawing motion.

What I claim as my invention is:—

1. A toy comprising a frame, a seesaw fulcrumed thereon, a member pivoted on each of the two arms of said seesaw, said two members being hingedly interconnected and having steps staggered with relation to one another and adapted to form a path between them for a ball adapted to alternatively depress said stepped members, and means for feeding single balls to said path.

2. A toy comprising a frame, a seesaw fulcrumed thereon, a member pivoted on each of the two arms of said seesaw, said two members being hingedly interconnected and having steps staggered with relation to one another and adapted to form a path between them for a ball adapted to alternatively depress said stepped members, a trough for said balls on the top of said path, and means for feeding a new ball from said trough when a preceding ball has left said path.

3. A toy comprising a frame, a seesaw fulcrumed thereon, a member pivoted on each of the two arms of said seesaw, said two members being hingedly interconnected and having steps staggered with relation to one another and adapted to form a path between them for a ball adapted to alternatively depress said stepped members, a trough for said balls on the top of said path, a lever pivoted on said frame and adapted to be depressed by a ball leaving said path, a thrust rod hingedly connected to said lever and adapted to feed a new ball from said trough to said path when said lever is depressed.

In testimony whereof I have affixed my signature.

WILHELM DAVID.
